PUMP AND VALVE FOR LIQUID
DISPENSING DEVICES

Henry T. Baggett and Henry D. Bolton, Houston,
Tex., assignors to Hughes Tool Company,
Houston, Tex., a corporation of Texas

Application May 28, 1934, Serial No. 727,994

7 Claims. (Cl. 225—16)

Our invention relates to pumps such as are employed in dispensing liquid from containers of comparatively small dimensions as for delivering drinks and beverages.

5 It is an object of the invention to provide a pump which may be employed to increase the fluid pressure in the container and which will maintain a fluid seal in the container when the pump is not operating.

10 Another object is to provide an outlet conduit which will be automatically opened when the delivery spout is moved into position to dispense the liquid. It is desired to provide an easily detachable spout or outlet tube which may be inserted into position and partly rotated to open the valve and deliver the liquid for use.

15 The invention resides in the means for preventing escape of fluid from the container when the device is not being operated and to easily 20 open the discharge pipe to dispense the liquid when desired.

In the drawing herewith Fig. 1 is a central vertical section through a container equipped with the invention, said container being partly 25 broken away.

Fig. 2 is a transverse section on the plane 2—2 of Fig. 1.

Fig. 3 is a detail of the device taken on the plane 3—3 of Fig. 1.

30 The container 1 here shown is of sheet metal with the end walls 2 and 3 depressed slightly below the end rims of the side walls 4. In the upper wall 3 is a supporting ring 5 fitted through an opening in said wall and extending within the container a short distance. Said ring is sealed in position by welding material and has an inwardly projecting flange 6 upon which is mounted a pump supporting nipple 7.

35 Said nipple 7 has a flange at its upper end 40 engaging above the packing ring 8 on the flange 6. A gland ring 9 is screwed in above the nipple to hold it in sealing engagement above the seal ring. At the lower end of the nipple is attached the pump cylinder 10. A cap member closes the lower end of said cylinder, said cap having an axial opening to allow the eduction tube 12 to work therethrough. A stuffing box 13 seals about the tube 12 in the cap.

45 There is an outlet for the lower end of the cylinder through a passage 15 to the outer periphery of the cap 11. Said outlet passage discharges into a peripheral recess in which is fitted an elastic band 15 of rubber or similar material which acts as a valve to prevent the passage of fluid inwardly to said outlet.

The eduction tube 12 is slidably supported adjacent its upper end by a web or partition 16 in the nipple 7 with fluid passages therethrough. The upper end of the tube 12 is screwed into the lower end of a cup shaped member 17 acting as a valve chamber. It has a central recess, the lower wall of which has a passage 18 therein arranged off center and connecting with the tube 12.

5 In the lower end of the recess is a circular 10 plate or disc 19 of compressible material such as rubber. Said disc is held from rotation by an eccentric pin 20 and has an opening 21 registering with the opening 18.

Above the disc 19 is a rotary valve member 15 22 of the same outer diameter as said disc. The lower end of the valve engages the disc and there is a passage 24 in the valve inclined from an upper recess 25 to register, when in one position with the passage 21 in the disc. Said valve 20 is reduced in diameter above its lower end to accommodate a stuffing box 23 the gland of which is screwed within the upper end of the valve chamber.

Above the disc 19 is a rotary valve member 15 22 of the same outer diameter as said disc. The lower end of the valve engages the disc and there is a passage 24 in the valve inclined from an upper recess 25 to register, when in one position with the passage 21 in the disc. Said valve 20 is reduced in diameter above its lower end to accommodate a stuffing box 23 the gland of which is screwed within the upper end of the valve chamber.

The recess 25 is tapered to fit with the tapered lower end 26 of the outlet spout 27 which, as shown, is approximately U-shaped. The end of the spout engaging within the valve has a laterally extending pin 28 which, as seen in Fig. 3, extends entirely through the spout and preferably off center, so as not to be exactly diametrically of the recess 25. This pin engages in notches 29, shown in dotted lines in Fig. 1, formed in the upper end of the valve member. Said pin is off center so as to avoid engaging the spout with the valve in a position reversed from the desired position with the outlet end of the spout extending in the right direction.

A plate or washer 30 is welded upon the spout in such position as to engage within a recess in the upper end of the gland 23. At one side said plate is cut away at 31 so as to present two shoulders 32 to engage with a pin 33 on the gland 23. This pin limits the rotation of the valve, it being understood that the valve is open at an intermediate position of said pin as seen in Fig. 3. The valve may be closed by rotation of the valve by means of the spout in either direction from said intermediate position.

The tube 12 has a plunger thereon within the 50 cylinder 10. Said plunger has a flexible cup 34 clamped upon a body 35 by a clamping plate 36. On the lower side of the plunger body is a sealing ring 37 which is adapted to engage upon the seat 38, projecting up from the cap 11, when said 55

valve chamber 17 is screwed downwardly into the nipple 7. The gland member 23 has opposite arms 39, as seen in Fig. 3, to serve as a handle in reciprocating the pump plunger.

- 5 The spout 27 is detachable and removable. When it is desired to pump air into the container 4 the valve assembly including the gland 23 and the valve chamber 17 are rotated to unscrew the same from engagement with the nipple 7. The 10 tube and piston may then be reciprocated to pump in the air through the passage 14 past the check valve 15. The valve chamber is then again screwed into place to bring the seal ring 37 against the seat 38 and prevent escape of air.
- 15 When it is desired to dispense liquid from the container, the spout is inserted into the seat in the valve plug 22 and the valve is then rotated to open position to allow the discharge of liquid to a glass or other container.
- 20 The tapered fit of the spout with the valve plug makes a tight seal therewith before the pin 28 is entirely to the bottom of the notches 29, thus allowing for a close sealing fit even after wear has occurred.
- 25 What we claim as new is:
  1. A container, a pump cylinder supported therein, an eduction tube extending through said cylinder to project below the same, a plunger on said tube within said cylinder, a cap on said cylinder sealing about said tube, an air passage through said cap, means on said plunger to seal said passage, means on said tube to reciprocate the same and means to latch said plunger into position to close said seal.
  - 30 2. A container, a pump cylinder supported in sealing engagement in said container, a cap at the inner end of said cylinder, an eduction tube extending through said cylinder and fitting slidably through said cap, a plunger on said tube within said cylinder, an outlet passage through said cap, a seat about the upper end of said passage, a sealing member on said plunger adapted to engage said seat, a valve chamber at the upper end of said tube, said valve chamber being adapted to be screwed into position to force said sealing member upon said seat.
  - 35 3. A container, a pump cylinder supported in sealing engagement in said container, a cap at the inner end of said cylinder, an eduction tube extending through said cylinder and fitting slidably through said cap, a plunger on said tube within said cylinder, an outlet passage through said cap, a seat about the upper end of said passage, a sealing member on said plunger adapted to engage said seat, and means at the upper end

of said tube associated with said cylinder to engage said tube in position with said sealing member closing said passage.

4. The combination of a container, a cylinder projecting therein and having a sealing engagement therewith, a cap closing the inner end of said cylinder, an eduction tube extruding through said cylinder and said cap, an outlet passage from said cylinder to said container in said cap, a plunger on said tube within said cylinder, means whereby said tube and plunger may be reciprocated, and a check valve for said outlet passage comprising an elastic band held resiliently over the said outlet.

5. The combination of a container, a cylinder projecting therein and having a sealing engagement therewith, a cap closing the inner end of said cylinder, an eduction tube extruding through said cylinder and said cap, an outlet passage from said cylinder to said container in said cap, a plunger on said tube within said cylinder, means whereby said tube and plunger may be reciprocated, a valve chamber secured to the upper end of said tube, a valve therein, and a dispensing spout on said chamber removably engaging in said chamber and adapted to rotate said valve, said valve chamber being detachably connected with said cylinder.

6. A container, a pump cylinder supported in sealing engagement extending into said cylinder, an eduction tube extending through said cylinder, a plunger on said tube in said cylinder, a valve chamber detachably associated with the upper end of said cylinder and connected with said tube, a rotatable valve therein, a compressible disc below said valve in said chamber, passages through said valve, said disc and said chamber connecting with said tube, and a dispensing spout engageable in said passage to rotate said valve to bring said passages into or out of registration.

7. A container, a pump cylinder supported in sealing engagement extending into said cylinder, an eduction tube extending through said cylinder, a plunger on said tube in said cylinder, a valve chamber detachably associated with the upper end of said cylinder and connected with said tube, a rotatable valve therein, a tapered seat in said chamber, a passage from said seat to the lower end of said valve, a passage in said chamber connecting with said tube, and a dispensing spout shaped to make a sealing engagement in said seat and rotate said valve to bring said passages into or out of registration.
